(57) CLAIM

The ornamental design for a seat, as shown and described.

DESCRIPTION

FIG. 1 is a front perspective view of a seat showing my new design in the form of a sofa;

FIG. 2 is a right side elevational view, the left side being a mirror image thereof;

FIG. 3 is a rear view thereof;

FIG. 4 is a top view thereof;

FIG. 5 is a front perspective view of a second embodiment showing my new design in the form of a chair;

FIG. 6 is a right side elevational view, the left side being a mirror image thereof;

FIG. 7 is a rear view thereof; and,

FIG. 8 is a top view thereof.

The broken lines showing leg members are for illustrative purposes only and form no part of the claimed design.
